UNITED STATES PATENT OFFICE.

JAMES WILSON, OF STRATFORD, CONNECTICUT, ASSIGNOR TO JOHNS-MANVILLE INCORPORATED, A CORPORATION OF NEW YORK.

GAUGE FOR LAYING ROOFING.

1,405,083.

Specification of Letters Patent. Patented Jan. 31, 1922.

Application filed September 23, 1920. Serial No. 412,187.

To all whom it may concern:

Be it known that I, JAMES WILSON, a citizen of the United States of America, residing at Stratford, county of Fairfield, State 5 of Connecticut, have invented certain new and useful Improvements in Gauges for Laying Roofing, of which the following is a specification.

My invention relates more particularly 10 to the laying of prepared roofing which consists of sheets of waterproof fabric usually 32 or 36 inches wide and of varying lengths. These sheets are rolled up at the place of manufacture and shipped to the place of use 15 where they are nailed to the roof deck, flat-headed nails being frequently employed for this purpose. These sheets of roofing are laid with their edges over-lapping, the nails passing through the overlapped portions, 20 and it is desirable that the amount of overlap of all sheets should be uniform as well as the spacing of the nails, and that the nails along each lap should be driven in line each with the others. My invention provides 25 a simple but effective device for accomplishing these results and generally facilitating the laying of the roofing. The best form of apparatus embodying my invention at present known to me is illustrated in the 30 accompanying sheet of drawing in which—

Fig. 1 is a plan view of a portion of a roof, parts being broken away, showing the gauge in one of the positions it would occupy in use.

Fig. 2 is a cross section on line 2—2 of Fig. 1.

Fig. 3 is an enlarged plan view of the gauge, parts being broken away, and Fig. 4 is a cross section on line 4—4 of Fig. 3.

Throughout the drawings like reference characters indicate like parts:

1 is the roof deck and 2, 3, 4 and 5 represent sheets of prepared roofing nailed, or to be nailed thereto. These sheets are laid on 45 an inclined roof deck or surface with their longer dimensions horizontal, so that the longer lap between each two adjacent sheets is called the "horizontal lap" and the shorter lap is called the "vertical lap." According to 50 the prevailing custom in the art, the width of the horizontal lap is 2 inches and that of the vertical lap 3 inches, and the nails are set with their centers three-quarters of an inch back from the outer edge of each 55 lap and 2 inches apart, all as indicated by

the relative dimensions shown in the drawing.

6 is the gauge which is made of a strip of wood or other stiff material, usually 36 inches long and 2 inches wide, having one edge, as 9, 60 beveled. In one edge of the strip, preferably the one not beveled, is cut a series of transverse slots 7, 7, two inches between center lines, each wide enough to receive a nail (usually three-sixteenths of an inch in diameter), and deep enough to allow such a nail, when placed at the bottom of a slot, to have its center distant three-quarters of an inch from the line of the slotted edge of the gauge. 8, 8 are half slots formed at either 70 end of the gauge. The unslotted edge of the gauge may be given the usual graduations showing inches and fractions thereof, and one of these, at the 3-inch point from one end, may be prolonged as shown at 13, or 75 otherwise distinguished.

In use the gauge may be laid along the edge of any one sheet of roofing, already 80 in position, to indicate the proper width of horizontal lap, and the adjacent sheet laid over it with its overlapping edge registering with the inner edge of the gauge. This will locate the loose sheet in the proper position to give the desired 2-inch horizontal lap 11. The 3-inch vertical lap 12 is 85 similarly measured by the graduation 13. The loose sheet being properly located, the gauge is placed along one edge, such as the edge of the horizontal lap 11, and with the half slot 8 at one end engaging the last 90 nail in the next sheet, as shown in Fig. 1, said last nail having been driven only half way in. The nails 10 are then driven through the slots 7, 7, half way home, as indicated in Fig. 2. The gauge is then 95 swung up on the end nail as a pivot to similarly space the nails for the adjacent vertical lap. Then the gauge is removed and all the nails are driven home. The foregoing operations are repeated until the roof is covered 100 and all sheets nailed in position.

I preferably make the gauge of a strip a quarter inch thick and bevel one-half of one face down to a thickness of one-eighth inch at the edge 9, as indicated in Fig. 4. 105

Having described my invention I claim:

1. As a new article of manufacture a gauge for laying prepared roofing said gauge comprising a strip of stiff material having a series of slots in one edge, spaced 110

- apart by the distances at which the nails to be used in holding the roofing in position are spaced apart and of a depth equal to the distance which such nails are to be set back from the edge of each sheet of the roofing.
2. A structure such as set forth in claim 1 also having each end cut away to conform to the outline of one-half of one of the slots such as are therein described.

3. A structure such as described in claim 1 which has a width equal to the width of the overlap at the longer edges of the sheets of roofing, and has one edge beveled.

JAMES WILSON.
